Filed Dec. 27, 1963, Ser. No. 77,944

Term of patent 14 years

(Cl. D58—17)

FIG. 1 is a side elevational view of a combined support and holder for a trash receptacle, showing my new design;

FIG. 2 is a top plan view of the can bottom supporting bracket;

FIG. 3 is a bottom plan view of the bracket of FIG. 2;

FIGS. 4, 5 and 6 are vertical side elevational views of the bracket of FIG. 2 as seen from the front, side and rear, respectively;

FIG. 7 is an axonometric view of the novel handle engaging bracket of FIG. 1;

FIG. 8 is a side elevational view of another embodiment of a combined support and holder for trash receptacles showing my new design;

FIG. 9 is a top plan view of the dual can bottom supporting bracket;

FIG. 10 is a bottom plan view of the bracket of FIG. 9;

FIG. 11 is a vertical side elevational view of the bracket of FIG. 9, and

FIG. 12 is an axonometric view of the novel dual can handle engaging bracket of FIG. 8.

The portions shown in broken lines are for illustrative purposes only.

I claim:

The ornamental design for a combined support and holder for trash receptacle, substantially as shown and described.
